UNITED STATES PATENT OFFICE

101,183

DESIGN FOR A RANGE

Walter L. Vocke, University City, Mo.

Application July 15, 1936, Serial No. 63,873

Term of patent 14 years

To all whom it may concern:

Be it known that I, Walter L. Vocke, a citizen of the United States of America, residing at University City, Missouri, have invented a new, original, and ornamental Design for a Range, of which the following is a specification, reference being had to the accompanying drawing forming a part thereof.

The figure is a front perspective view of the range showing my new design.

The side opposite to that shown is like the side shown. The back of the range is substantially plain.

I claim:

The ornamental design for a range as shown and described.

WALTER L. VOCKE.
